CLAIM

The ornamental design for a stanchion for a beverage tap, as shown and described.

DESCRIPTION

FIG. 1 is a side elevational view of a stanchion for a beverage tap showing my new design, the undisclosed sides being the same in appearance as the side shown.

FIG. 2 is a top plan view thereof on an enlarged scale; and

FIG. 3 is a bottom plan view thereof on an enlarged scale.

FIG. 1.

Fig. 2.

Fig. 3.
